UNITED STATES PATENT OFFICE.

DOYEL PEARSON, OF MEMPHIS, TENNESSEE.

HOT-AIR FIRE-PLACE.

SPECIFICATION forming part of Letters Patent No. 322,634, dated July 21, 1885.

Application filed October 2, 1884. (No model.)

To all whom it may concern:

Be it known that I, DOYEL PEARSON, of Memphis, in the county of Shelby and State of Tennessee, have invented a new and Improved 5 Hot-Air Fire-Place, of which the following is a full, clear, and exact description.

The object of my invention is to more largely utilize fire-places for heating rooms, and also to provide for the special application of the 10 heated air; and to these ends it consists in the peculiar construction and arrangement of parts, as hereinafter described and claimed.

Reference is to be had to the accompanying drawings, forming part of this specification, in which similar letters of reference indicate corresponding parts in all the figures. 15

Figure 1 is a front elevation, partly sectional, of a fire-place embodying my improvements. Fig. 2 is a vertical section on the line $\alpha\alpha$ of 20 Fig. 1. Fig. 3 is a horizontal section, and Fig. 4 is a vertical section on line yy of Fig. 1.

The brick-work A is made with a recess for the fire-place, as usual. In this recess is the fire-box or heater, formed by a plate or casting, a , having side flanges, b , which extend to the front, as shown. The plate a inclines outward at the top, and the side plates set off from the brick-work, so as to form an air-space or box, c , between the plates and brick-work. d are the grate-bars, consisting of tubes set in the side plates, b , so as to allow passage of air from one side of the fire-box to the other. The air-space at one side is divided by a fixed partition, e , and into the smaller space thus inclosed an inlet, f , formed through the brick-work, leads from the outer air. From the top of the main air-space a pipe, g , leads upward and into the room at any desired place, or to other rooms, where it 40 may be fitted with a flexible pipe for conveying the heated air to a bed or other special place in the room.

The back plate, a , is formed with ribs h , that strengthen the plate, and also form air-spaces 45 to promote combustion.

In operation the fresh air from the outside enters at the inlet f , passes through the tubular grate-bars to the air-box, and from thence to the pipe g . In this passage the air becomes highly heated, and, coming directly from outside, is purer and fresher than the vitiated air of rooms.

There is shown at i an opening in the side plate, b , for admitting air from the air-box to the space beneath the grate to promote the 55 draft through the fire.

The use of cold air from outside in the manner described tends to keep the plates forming the fire-place from burning out, and a great amount of waste heat is utilized. 60

I am aware that a fire-place having an air-heating chamber back of the fuel-chamber for supplying heated air to warm other rooms is old; and I am also aware that tubes have been arranged across the upper part of the fuel-chamber, the said tubes communicating with the air-chamber in the rear of the fuel-chamber, and I therefore do not claim such invention. 65

Having thus fully described my invention, I 70 claim as new and desire to secure by Letters Patent—

1. The herein-described fire-box or heater, consisting of the forwardly inclined back plate, a , having side flanges, b , and provided 75 with the ribs h , and the inclined plate e , projecting from one side flange and forming a partition when the heater is in position, and the tubes d , having their ends passed through the side flanges and forming grate-bars, as set 80 forth.

2. In a fire-place heater, the back plate, a , provided with the ribs h , the side plates, b , the tubular grate-bars d , and the partition e , in combination with the inlet f and outlet g , 85 substantially as herein shown and described.

DOYEL PEARSON.
